H. H. SIMMS.

RAZOR.

APPLICATION FILED SEPT. 23, 1909.

1,133,328.

Patented Mar. 30, 1915.

UNITED STATES PATENT OFFICE.

HAROLD H. SIMMS, OF ROCHESTER, NEW YORK, ASSIGNOR TO AUTO STROP COMPANY, OF NEW YORK, N. Y., A CORPORATION OF NEW YORK.

RAZOR.

1,133,328.

Specification of Letters Patent. Patented Mar. 30, 1915.

Original application filed April 17, 1909, Serial No. 490,564. Divided and this application filed September 23, 1909. Serial No. 519,219.

To all whom it may concern:

Be it known that I, HAROLD H. SIMMS, of Rochester, in the county of Monroe and State of New York, have invented certain new and useful Improvements in Razors; and I do hereby declare the following to be a full, clear, and exact description of the same, reference being had to the accompanying drawings, forming a part of this specification, and to the reference-numerals marked thereon.

The present invention relates to razors, the subject matter of this application having been divided from an application filed by me on the 17th day of April, 1909, Serial No. 490,564.

The object of the invention is to provide a safety razor in which the guard or guards may be moved to expose the blade edge or edges for stropping without being removed from the razor, so that there is no possibility for the loss of any parts of the device.

To these and other ends the invention consists in certain improvements and combinations of parts all as will be hereinafter more fully described, the novel features being pointed out in the claims at the end of the specification.

In the drawings: Figure 1 is an enlarged transverse section of one embodiment of the invention with the parts in position for shaving; Fig. 2 is an enlarged side view of the razor with parts in section, and Fig. 3 is a detail view of the guard frame on a smaller scale.

The blade holder of the illustrated embodiment of the invention comprises preferably a supporting member or plate 1 having positioning means or pins 2 projecting therefrom for passage through openings in a double edged blade 3, the blade being held to the supporting member by any suitable means as by a retaining member or plate 4 which in this instance is pivoted at one end to the supporting member as at 5 and secured at its other end by a spring latch 6.

The blade holder may be carried by a frame 7 which is connected thereto away from the center or middle portions so that a strop may be brought to engage the edge or edges of the blade. In this instance the frame 7 is rigidly secured to one end only of the blade holder and is preferably in-

tegral with the supporting plate 1 thereof, so that a space is formed opening at the other end of the blade holder into which a strop or other sharpener may be introduced laterally. This frame serves as a rigid connector between the blade holder and a handle 8 which is preferably hollow and has at one end an enlarged portion 9 internally threaded to engage an externally threaded boss 10 on the frame 7.

Coöperating with the edges of a blade held by the holder are two guards 11 formed by longitudinally notched edges on a guard frame or plate 12 which in this embodiment is movable on the razor to expose the blade edge or edges. Preferably the side faces 13 of the frame 7 serve as guides for one end of the guard frame 12 which has guide projections 14 coöperating with the guide faces 13 so that the guard frame may move away from the blade holder to provide a space for a sharpener. A rod 15 may project from the under face of the guard frame to enter the hollow handle 8 at the upper end of the latter when the frame is moved away from the blade holder, and with this rod may co-operate means for retaining the guard frame in coöperative relation with the blade holder, said means consisting in this instance of a nut 17 having a thumb portion 18 and rotatably mounted in the frame 7 to engage an enlarged screw threaded portion 16 on the rod 15.

Assume the parts are in the positions shown in Figs. 1 and 2 and it is desired to strop the blade. The nut 17 is operated by the thumb portion 18 to carry the guard frame away from the blade holder. After the threaded end 16 has passed through the nut the rod 15, which is of smaller diameter than the nut opening, drops into the hollow handle so that the guard frame will be located in the position shown in Fig. 2, being guided against rotation by projections 14 coöperating with guide faces 13. A strop or other sharpener is then passed between the guard frame and the blade holder and the razor is moved back and forth over the sharpener. At the end of each stroke the razor is tilted slightly in the opposite direction, so that opposite edges of the blade are brought into engagement with the sharpener. Of course only one

face of each edge is sharpened, but the other faces may be engaged by reversing the position of the blade in the holder.

A safety razor constructed in accordance 5 with this invention makes it possible to strop the blade within the holder which secures the blade during stropping without the disconnecting any parts of the device and the blade during stropping is rigidly 10 held relatively to the handle so that it is possible to secure any desired pressure on the sharpener.

I claim as my invention:

1. In a safety razor, the combination with 15 a blade and a blade holder having a supporting plate for coöperation with the blade substantially throughout the length of the latter, and also having means for securing said blade to said supporting plate, of a handle rigidly connected to the supporting plate at such a point that a space is provided for the passage of a strop or sharpener in a line transverse of the cutting edge of the blade supported by said plate, and a guard 25 for the blade movable on the razor relatively to the supporting plate and to the handle and from the plane of the blade to open said space for the passage of the strop or other sharpener.
2. In a safety razor, the combination with 30 a blade and a blade holder having a supporting plate for coöperation with the blade substantially throughout the length of the latter, and also having means for securing said blade to said supporting plate, of a handle having rigid connection with the plate at a point to provide a space at one side of the plate for the passage of a sharpener to engage with the blade in order to 35 move in a line transverse of the cutting edge of said blade, a guard for the blade movable relatively to said holder and to the handle to open such space for the passage of a sharpener, and a guide on which the guard is 40 adapted to move relatively to the handle to and from the plane of the blade.
3. In a safety razor, the combination with 45 a double-edged blade and a blade holder having a supporting plate adapted to co-operate with the blade substantially throughout the length of the latter and between the edges thereof to expose such edges for sharpening, and also having means for securing the blade to said supporting plate in such 50 position, of a handle rigidly connected to the holder at a point to provide a space at one side of said plate for the passage of a sharpener, and a guard frame having guards coöperating with both blade edges and movable on the razor relatively to the holder and to the handle and away from the plane of the blade to open a space between the blade holder and the guard frame for the 55 passage of a sharpener.
4. In a safety razor, the combination with 60

a blade and a blade holder having a supporting plate coöperating with the blade substantially throughout the length of the latter, and also having means for securing said blade to said supporting plate, of a handle, a frame rigidly connecting the handle and the supporting plate of the blade holder and having a space for the passage of a sharpener to engage the blade, and a guard for the blade movable on the razor within such space and relatively to the holder and the handle and away from the plane of the blade to permit such sharpener to engage the blade.

5. In a safety razor, the combination with 80 a blade and a blade holder having a supporting plate coöperating with the blade throughout the length of the latter, and also having means for securing said blade to said supporting plate, of a handle having a rigid connection with one end only of the holder at one end of a cutting edge of the blade, such connection providing a space at one side of the plate, and a guide on which the guard moves relatively to the handle and the holder within such space to expose the cutting edge of the blade for sharpening.

6. In a safety razor, the combination with 85 a blade and a blade holder having a supporting plate for coöperating with the blade substantially throughout the length of the latter, and also having means for securing said blade to said supporting plate, of a handle rigidly connected to one end only of the blade supporting plate at one end of a cutting edge of the blade to provide a space on one side of the holder for the passage of a sharpener, and a guard for the blade movable on the razor in said space and relatively 90 to the holder and the handle to expose the cutting edge of such blade.

7. The combination with a blade and a blade holder having a supporting plate coöperating with such a blade substantially throughout the length of the latter and also 110 having means for securing said blade to said supporting plate, a frame connected to the blade holder and formed with a space in proximity to the holder for the passage of a sharpener, a hollow handle secured to the frame, a guard for the blade, and a rod secured to the guard to support the same in coöperative relation with the holder and movable into the hollow handle when the guard is moved away from the blade.

8. The combination with a blade and a blade holder having a supporting plate coöperating with such a blade substantially throughout the length of the latter and also 115 having means for securing said blade to said supporting plate, of a supporting frame for the holder formed with a space in proximity to the holder for the passage of a sharpener, a hollow handle, a guard for the blade, a rod secured to the guard, and 120

130

means coöperating with the rod for holding the guard in coöoperative relation with the blade in the holder.

9. The combination with a blade and a blade holder having a supporting plate coöperating with such a blade substantially throughout the length of the latter and also having means for securing said blade to said supporting plate, of a supporting frame for the holder formed with a space in proximity to the holder for the passage of a sharpener, a hollow handle, a guard for the blade, a rod secured to the guard and having a screw thereon adapted to operate in the handle, and a nut for coöperation with the screw on the rod.

10. The combination with a blade and a blade holder having a supporting plate coöperating with such a blade substantially throughout the length of the latter and also having means for securing said blade to said supporting plate, of a frame rigidly secured thereto and provided with a space in proximity to the holder for the passage of a sharpener for the blade, a hollow handle secured to the frame, a guard for coöperation with the blade, a rod secured to

said guard having screw threads thereon, and adapted to enter the handle, and a nut for coöperation with said threads to hold the guard in position relative to the blade. 30

11. In a safety razor, the combination with a blade supporting plate, and means for clamping a blade to the upper face thereof, of a hollow handle connected to the supporting plate, a guard movable relatively to the under side of the blade supporting plate, and a rod adjustable in the handle and connected to the guard. 35

12. The combination with a blade supporting plate, and a guard movable relatively thereto, of a hollow handle secured to one of said parts, a rod adjustable in the handle and secured to the other of said parts, blade clamping means carried by said blade supporting plate to hold the blade during the relative movement between the guard and the plate and a nut coöperating with the rod to hold the guard in coöoperative relation to the blade supporting plate. 40 45 50
